[57] CLAIM

The ornamental design for an imitation golf ball shaped container with attachment for key chain, as shown and described.

DESCRIPTION

FIG. 1 is an isometric view of an imitation golf ball shaped container with attachment for key chain incorporating my new design;

FIG. 2 is a front view thereof;

FIG. 3 is a right side view thereof; the left side view being a mirror image thereof;

FIG. 4 is a rear view thereof;

FIG. 5 is a top view thereof; and,

FIG. 6 is a bottom view thereof.

The broken line showing of a chain, in FIG. 1, is for illustrative purposes only and forms no part of the claimed design.
